UNITED STATES PATENT OFFICE.

JOHN JOSEPH SAMPSON, OF DUBLIN, IRISH FREE STATE.

APPARATUS FOR CASTING MOLTEN SUBSTANCES.

Application filed March 5, 1925, Serial No. 13,315, and in Great Britain and Ireland March 14, 1924.

This invention relates to casting articles from molten material and whilst primarily directed to producing seals from molten lead, it is applicable for producing articles generally from molten metal, wax or other fusible substances, and has for its principal object the utilization of compressed air for forcing the molten substance into the moulds. A further object is to provide a method of and means for automatically producing the article in the finished state.

According to the invention, a compressed air pump is located in a vat containing the molten material to be moulded, and is formed with valve controlled inlets for the molten material and compressed air respectively, together with an outlet or discharge nozzle. Said pump is movably mounted, and actuated from a crank or cam shaft through suitable mechanism to move the outlet orifice towards and away from the mould. The latter is in two or more parts synchronously actuated from the same shaft, as also is the valve controlling the admission of compressed air, and the cutter to sever the moulded article from the "gate." A mould stripper may be actuated in like manner, or it may be actuated by one of the mould parts striking against it.

The accompanying drawings show one convenient form of the invention, in which:—

Fig. 1 is a plan.

Fig. 2 is a sectional elevation on line 2—2.

Fig. 3 is a sectional elevation on line 3—3.

Fig. 4 is an enlarged sectional elevation of the parts of the mould.

Fig. 5 is a sectional elevation of the pump.

Fig. 6 is a detail of the ejector cam plate, and

Fig. 7 is a sectional elevation showing a modified form of the pump shown in Fig. 5.

The apparatus shown comprises a base 2 having lugs 3, 3 in which is mounted a crank shaft 4. The base is further provided with bosses 5 and 6 which are provided with adjustable slide bearings 7 and 8 respectively.

The base is further provided with a lug 9 and a facing 10 having a pair of lugs 11, 11 and an opening 12 therein. Slidably mounted in the bearings 7 and 8 is a hexagonal slide bar 13, one end of which is connected by a link 14 to the crank pin 15 of the crank shaft 4, and the other end of which is provided with a lug 16. Secured to the top

side of the hexagonal slide bar 13 is a cam plate 17 formed with cam slots 18. Mounted on the facing 10 is a guide block 19 in which is slidably mounted the front die 20 and in which is secured the back die 21 and below 60 which is slidably mounted a knife 22. The rear end of the front die 20 is pivotally connected to a rod 23 slidably mounted in the lug 16 of the slide bar 13, which rod is provided with a compensating spring 24 and 65 an adjusting nut 25. An adjustable screw stop 26 is provided in the lug 16 and has a lock nut 27, and the end of the stop is adapted to engage the back end of the die 20. The knife 22 is provided at one end 70 with a conical hole or port 28 and at the other end is pivotally connected to the centre of a link 29 pivotally mounted by one end at 30 to the facing 10, and connected at the other end to a slide bar 31. The slide bar 75 31 passes through the bosses 5 and 6, a return spring 32 and adjusting nut 33 being provided on the end thereof.

The slide bar 31 is formed with a plate like portion 34 having slots 35 and a notch 36 on its edge adjacent to the slide bar 13.

Below the part 34 of the slide bar 31 is a release plate 37 formed with a curved recess 38 registering normally with the notch 36 and secured to the base 2. A spring operated pawl 39 is mounted on the slide bar 13 and engages with the release plate 37 sliding in its movement along the edge thereof. A part of the pawl however extends above the release plate and is adapted to engage with 90 the notch 36 of the slide bar 31 when in the recess 38.

Slidably mounted in the lugs 11 are cores 40 the outer ends of which are reduced and springs 41 and collars 42 are disposed thereon, the collars 42 being secured thereby through pins 43 on which also are arranged links 44.

Mounted on pivots 45 on the base 2 are levers 46 having at one end rollers 47 working in the cam slots 18 the other ends of the levers being connected to the respective links 44. The springs 41 are thus arranged so as to transmit the closing action of the levers 46 to the cores 40, which therefore can 105 adjust themselves against the sides of the dies.

Mounted at the end of the base 2 and directly opposite the die 20, is an ejector for clearing the dies and comprises a frame 48 110

secured to the facing 10 at the end of the opening 12. Slidably mounted in the bottom of the frame 48 is a toothed rack 49 having an extension 50 which passes through 5 a resistance plate 51 secured by the bolts 52 to the frame 48. A return spring 53 is provided on the extension 50. Transversely mounted in the frame 48 is a spindle 54 having a central toothed wheel engaging with 10 the rack 49. Pivotedly mounted on the spindle on each side of the wheel 55 are ejector arms 56 which pass through a guide plate 57 provided with slots 58 the guide plate being secured to the frame 48. The 15 end of the rack 49 is adapted to be engaged by the forward end of the forward die 20 on which a projection 59 is provided for that purpose.

Below the dies is arranged a tank or 20 holder 60 for the molten material being suitably heated and within the tank is arranged a compressed air pump 61 mounted on vertical slide rods 62 passing through extensions 63 of the lugs 11. The pump is adapted to be raised and lowered in the tank by 25 means of the slide rods 62 the upper ends of which are provided with a cross piece 64 adjustably secured thereto. In the center of the cross piece 64 is secured a fulcrum bolt 30 65 engaging one end of a lever 66 pivotally mounted in the lug 9 on the base 2, the other end of which lever 66 being provided with a roller 67 to engage a cam 68 on the crank-shaft 4. The tank 60 is provided with a 35 chute 69 arranged below the ejector.

The compressed air pump 61 comprises a U-shaped tube having a cone shaped delivery nozzle 70 an air inlet valve seat 71 and ball valve 72 and an inlet 73 and ball valve 74 40 for the molten material. Retaining pins 75 are provided to keep the ball valves adjacent to their seatings.

On the base 2 is also mounted an air valve comprising a body piece 76, having a valve 45 plate 77 and a slide valve 78. An air inlet 79 is provided for coupling to the source of compressed air and a flexible delivery pipe 80 is connected from a port 81 in the valve plate 77 to the pump 61. The slide valve 50 78 is kept against the valve plate 77 by a spring 82 adjusting nut 83 and washer 84 arranged on a projection 85. The valve plate 77 rests on the base 2 and forms a guide for an operating rod 86 one end of which is 55 formed with a hole to receive the end of the projection 85 and the other end of which is formed with a hook or lug 87 the forward end of which is sloped off. An abutment piece 88 is secured to the base 2 and a return 60 spring 89 is provided for the rod 86.

An articulated operating arm comprising links 90, 91, 92 and 93 pivoted together is pivoted by one end of the link 90 to a bracket 94 on the base 2. A roller 95 is provided on 65 the link 90 and positioned to engage a cam

96 on the end of the crank shaft 4. The link 91 passes through a bracket 97 secured to the base and is provided with a return spring 98 and collar 99. The link 92 slides in a block 100 mounted on the base 2, and 70 the link 93 slides on the abutment piece 88 and is formed with a hooked end 101 to engage with the hook 87 of the valve operating rod 86.

In Fig. 7 a modified form of pump is illustrated, wherein the ball inlet valve 74 is replaced by an automatic valve 101a. Said automatic valve is fitted at its upper end with a propeller 102, which as the pump rises and falls, rotates the valve and ensures 75 of a constant liquid tight fit. A short pivoted lever 103 with a horizontal blade 104 is also attached to the valve so that when the pump is raised, the resistance of the liquid against the blade closes the valve, and 80 as the pump is lowered, the resistance of the liquid opens the valve.

The operation of the improved machine will be as follows: Assuming the crank pin 15 to be at six o'clock and turning clockwise, 90 then from six to nine or through 90°, the slide bar 13 is drawn backwards and with it the front portion 20 of the die. Simultaneously the cam plate 17 fixed to it causes the core members 40 to move inwards until 95 the complete die is formed at the extreme position. During this movement the cam 68 has actuated the lever 66 to raise the pump nozzle 70 until it projects into the complete die through the opening 28 in the knife 22 100 provided to cover the gate. With the parts in this position the valve cam 96 momentarily opens the valve 78 to admit compressed air to the pump 61 which ejects the required amount of molten lead into the die to form 105 the required seal.

Further rotary movement of the crank shaft 4 causes the slide bar 13 to travel forwardly to open the die and simultaneously the pump 61 is lowered while the pawl 39 on the slide bar 13 momentarily engages the notch 36 in the knife slide 34 and moves the knife 22 forward to cut off the gate of the seal, the slide 34 being released by the pawl 39 as soon as it leaves the curved notch 38 in the plate 37. Continued forward movement of the slide bar 13 causes the core members 40 to be moved clear of the die after which the adjustable abutment 27 engages the rear end of the forward or movable die 20 and 110 carries it together with the completed seal lodged therein forwardly until its projection 59 strikes the stripper rack 49 when the stripper arms 56 are caused to move downwards and inwards to grip the seal by entering the core poles and deliver it to a chute 115 59.

If desired the compressed air may be caused to traverse a pipe in the molten substance before entry to the pump 61 in order 120 125 130

to pre-heat the same but usually the molten material in the tank 51 will be sufficiently heated.

By these means lead seals and other articles are readily cast from molten substances, while said substance is completely under control and liability for the pump nozzle 70 to become blocked by the material solidifying is obviated as it is found in practice that immediately the air pressure is released by the valve 78 as shown in Fig. 3 the molten material recedes from the nozzle 78 before solidification can take place.

What I claim is:—

1. Apparatus for casting articles from molten material comprising in combination, a tank for the material, means for heating the tank to melt the material, a compressed air "pump" submerged in the molten material, means for supplying compressed air to the pump to eject the material, automatic valve-controlled inlets in the pump for the molten material and for the air, a mould arranged above the tank, and means for raising the pump into engagement with the mould for filling it with the ejected molten material, as set forth.

2. Apparatus for casting articles from molten material comprising in combination, a tank for the material, means for heating the tank to melt the material, a compressed air "pump" submerged in the molten material, means for supplying compressed air to the pump to eject the material, automatic valve-controlled inlets in the pump for the molten material and for the air, a mould, arranged above the tank, consisting of a stationary die and moving die, and means for raising the pump into engagement with the mould for filling it with ejected molten material, as set forth.

3. Apparatus for casting seals from the

molten material comprising in combination, a tank for the material, means for heating the tank to melt the material, a compressed air "pump" submerged in the molten material, means for supplying compressed air to the pump to eject the material, automatic valve-controlled inlets in the pump for the molten material and for the air, a mould, arranged above the tank, consisting of a stationary die and a moving die, slidably mounted cores adapted to be moved into and out of the mould, means for raising the pump into engagement with the mould for filling it with the ejected material a knife below said dies to cut the sprue, and means for stripping the seal from the mould, as set forth.

4. Apparatus for casting seals from molten material comprising a tank for the material, means for heating the tank to melt the material, a compressed air "pump" submerged in the molten material, consisting of a discharge chamber, adapted to be immersed in the molten material, an outlet nozzle therefrom, an automatic float controlled non-return inlet therein for the molten material, and a compressed air inlet having a float controlled non-return valve, means for supplying compressed air to the said pump to eject the material, a mould, arranged above the tank, consisting of a stationary die and a moving die, slidably mounted cores adapted to be moved into and out of the mould, means for raising the pump into engagement with the mould for filling it with the ejected material, a knife below said dies to cut the sprue, and means for stripping the seal from the mould.

In testimony whereof I have signed my name to this specification.

JOHN J. SAMPSON.
